Primary Examiner—Freda S. Nunn*Attorney, Agent, or Firm*—Banner, Birch, McKie & Beckett[57] **CLAIM**

The ornamental design for an electronic computer, as shown and described.

DESCRIPTION

FIG. 1 is a top, front and right side perspective view of an electronic computer showing my new design in an open position;

FIG. 2 is a front elevational view thereof;

FIG. 3 is a top plan view thereof;

FIG. 4 is a bottom plan view thereof;

FIG. 5 is a left side elevational view thereof;

FIG. 6 is a rear elevational view thereof;

FIG. 7 is a front elevational view thereof in a closed position;

FIG. 8 is a right side elevational view thereof in a closed position;

FIG. 9 is a top plan view thereof in a closed position;

FIG. 10 is a top, front and right side perspective view of a second embodiment thereof;

FIG. 11 is a front elevational view thereof;

FIG. 12 is a top plan view thereof;

FIG. 13 is a bottom plan view thereof;

FIG. 14 is a left side elevational view thereof;

FIG. 15 is a rear elevational view thereof;

FIG. 16 is a front elevational view thereof in a closed position;

FIG. 17 is a right side elevational view thereof in a closed position; and,

FIG. 18 is a top plan view thereof in a closed position.
